MACHINE FOR DISPLAYING AND DISPENSING SOAP TABLETS OR THE LIKE ARTICLES

Benjamin Cramp, Barkingside, Ilford, England

Application May 18, 1938, Serial No. 208,517
In Great Britain May 31, 1937

4 Claims. (Cl. 312—64)

This invention relates to machines for displaying and dispensing soap tablets or the like articles and has for its object to provide an improved machine for this purpose.

According to the present invention there is provided a machine for displaying and dispensing stacked soap tablets or the like articles comprising a base member having a delivery side, a track along which is guided the lowermost article of the stack, said track being formed between a snail cam and a guide secured to the top of said base member, a discharge aperture to said track, a storage element for the stacked articles rotatably secured above said snail-cam, and with its axis of rotation perpendicular to the plane of said snail-cam, means for rotating said storage element, a discharge orifice to said storage element, a bridge-member crossing said discharge orifice, the arrangement being such that when the rotating mechanism is operated, the guiding face of the snail-cam displaces the centre of gravity of the lowermost stacked tablet, the cam moving the bottom of the tablet outwards whilst the bridge member retains the top of the tablet in its original position, thereby displacing the centre of gravity of the tablet, so that the weight of the tablet tends to pull the tablet automatically down into a discharge position, the tablet being retained on the slant by the internal face of the guide, until the tablet is rotated in line with the delivery aperture, when the resistance of the outside guide is removed, and the weight of the tablet automatically pulls the tablet down into the delivery position.

The article may, during rotation of the column, revolve about a double track cam and be caused to change its position from the vertical to a suitable angle, so that immediately said article leaves the cam and passes a delivery opening, the article will assume the horizontal position by its own weight.

The article may come to rest horizontally partly in the delivery aperture and partly in the column to facilitate manual withdrawal.

The dispensing means may be actuated by spring controlled pawl and ratchet means operated by a lever arrangement normally manually accessible.

The accompanying drawings illustrate one form of device made in accordance with this invention, wherein:

Fig. 1 is a perspective view of the device;

Fig. 2 is a plan thereof with the detachable cover removed;

Fig. 3 is a section on line 3—3, Fig. 1;

Fig. 4 is a section on line 4—4, Fig. 2;

Fig. 5 is a plan of the operating mechanism;

Fig. 6 is a front elevation of the operating mechanism;

Fig. 7 is a rear elevation of the operating mechanism;

Fig. 8 is a section on the line 8—8, Fig. 6.

In the example illustrated I provide a stationary base 2 constructed in box form and having a top-cover 3. On the underside of the cover 3 is a mechanism comprising an operating lever 4 adapted to pivot in suitable bearings 5a, 5b, secured to the bottom 6 of said base 2. The lever 4 is also adapted to extend through a vertical slot 8 formed in the base. This lever 4 is provided with a finger plate 9 so that it may be manipulated by finger pressure. The lever element 4 is arranged to actuate a bevel gearing comprising a toothed quadrant 10, disposed on an arm 11 rigidly secured to said lever 4. The said toothed quadrant 10 engages a bevel pinion quadrant 12 secured to a boss or sleeve 13 adapted to rotate on a vertical shaft 14. A transverse stop 15 is passed through the shaft 14. Secured to said pinion 12 is an arm 16 provided with a lug 17 to which is fixed a flat spring 18 wherein a rectangular hole or slot 19 is formed. Above the stop 15 on the shaft 14 slides a boss or sleeve 20 to which is secured a ratchet wheel 21 having four teeth 22 at 90° from each other. The side 23 of the ratchet wheel 21 remote from the sleeve 20 has recesses 24 along a diameter of said wheel 21 adapted to receive the arms of the stop 15 so as to limit the downward motion of the ratchet wheel 21. The end of sleeve 20 remote from the ratchet wheel is crowned with teeth 25 adapted to form a clutch by engaging with corresponding recesses 26 in a circularly recessed part 27 of a square plate 28 having shoulders at 29 and sliding on shaft 14 as an axis. The side 30 of the plate 28 remote from the circular recess 27 is squarely recessed at 31. A square plate 32 of the same size as plate 28 slides on shaft 14 on the side of plate 28 remote from the ratchet wheel 21 for a purpose hereinafter to be described. The end of the shaft 14 adjacent the plate 32 is provided with a screw thread 33 and a nut 34.

Returning now to the bearings 5a, 5b, these bearings are both rigidly secured to or cast in one with a base plate 35. A standard or abutment 36 supports bearings 5a and a socket 37 supports bearings 5b. Socket 37 supports the lower end of the vertical shaft 14. A ball 38 is inserted in the bottom of socket 37 for the end of shaft 14 to ride on. The lever 4 is secured in its

bearings by means of a pin 39 which passes through a boss or sleeve 40 at the junction of lever 4 and arm 11 and at its ends extends into the bearings 5a, 5b. To facilitate fixing in position bearing 5a has a hole large enough to permit of the passage therethrough of pin 39. One end of pin 39 is shouldered so as to engage in a shoulder seating in bearing 5b and the other end of the pin 39 is prevented from working back out of bearing 5a by a transverse pin 41 passing through a hole 42 in the outer end 43 of the bearing 5a.

Lever 4 is provided with a projection 44 adapted to engage abutment 36 and limit the upward motion of said lever. From a lug 45 on foot 15 step bearing 37 a pin 46 projects upwardly and holds a bent end 47 of a coiled spring 48 of which the other bent end 49 is held by a pin 50 projecting downwardly from the underside of arm 16. This spring 48 always tends to force arm 16 to 20 return to its initial position after lever 4 has been depressed. Consequently the toothed quadrant and pinion 10, 12 and therefore lever 4 always return to their initial position after lever 4 has been depressed and released. Standard 25 or abutment 36 has an upwardly projecting pin 51 on its upper end which engages in a suitable socket 52 in the underside of the top cover 3 of the base. Pins 53 project from the lower side of the base plate 35, and engage in suitable 30 sockets 54 in the bottom 6 of the base. Pins 53, 54 are thus adapted to hold the base plate 35 and therefore the bearings 5a, 5b in position.

To the upper end of abutment 36 on the side remote from bearing 5a is secured a flat oblong 35 spring 55 having a rectangular hole 56 adapted to engage with the teeth 22 of ratchet wheel 21 and prevent its turning in a clockwise direction. On the upper face 57 of the top cover 3 of the base there is a snail cam 58 disposed centrally about the orifice 59 through which the shaft 14 of the multiple column detachable storage element 60 passes. The example illustrated shows four columns. Also fixed to said upper face 57 and in association with said cam 58 there is a guide 61. The external face 62 of the cam 58 and the internal face 63 of the guide 61 form a track in which the ends of the articles 64 stand in the multiple column dispenser engage and rest. An aperture 65 formed in the guide 61 already referred to through which articles can pass when ejected. From aperture 65 the articles pass onto a delivery member 66 forming part of the stationary base 2, so that the article being delivered extrudes beyond the front of said delivery member 66 to permit of the fingers extracting the article from the dispenser when required. In conjunction with this arrangement each channel 67 of the multiple column storage element 60 is provided with bridge members 68 on which the glass front 69 of the channel rests. The said bridge member 68 is so positioned in the channel 67 that a rectangular orifice 70 exists below it to allow of articles 64 passing underneath when being ejected. In the example illustrated the 65 storage element 60 is of square cross-section and is provided with four vertical storage channels 67 facing the four sides of the square. The glass fronts 69 are formed by panels adapted to slide in slots 71 in the sides 72 of the channels 67 so that the articles 64 can be seen. The storage element 60 is provided with a suitable cover 73 attached thereto by a chain 74. The backs 75 of the storage channels 67 are interconnected by tongues 76 and grooves 77 to form a central 78 passage 78 square in cross-section. Passage 78

is transversely grooved at 79 at a suitable place. Plate 32 is disposed in said grooves at right angles across said channel during the construction of the storage element 60. A transverse stop 80 is disposed between the end of the snail cam 58 and the opposite wall of guide 61. Plate 32 has a medial orifice 81 through which shaft 14 can pass.

In operation assuming that the parts are disassembled the base-plate 35 is placed in position 10 on the bottom 6 of base 2 so that pins 53 engage in sockets 54, lever 4 projecting through slot 8. Boss or sleeve 13 is then slid correctly on to shaft 14 and so is boss or sleeve 20, on opposite sides of stop 15, the springs 18 and 55 by means of 15 the rectangular holes 19 and 56 being brought into correct engagement with the teeth 22 of ratchet wheel 21. The shaft 14 is placed in its socket or foot step bearing 37 so that quadrant 10 and pinion 12 engage. Spring 48 is connected to pins 46, 50 by its bent ends 47, 49 so as to urge the quadrant pinion 12 in a clockwise direction. Square plate 28 is slid on to shaft 14 so that its internal recesses 26 engage with teeth 25 on sleeve 20. The top cover 3 is slid over shaft 14, which passes through orifice 59, and permanently secured in position. The storage element 60 is placed on shaft 14 so that this shaft slides through passage 78 and the bottom of passage 78 engages on the shoulders 29 of 30 square plate 28 and shaft 14 slides through the orifice 81 of plate 32. Nut 34 is screwed home on the end of shaft 14 to hold the assemblage firmly together.

The glass fronts are slid into position. The storage channels 67 are filled with articles 64, soap tablets in the present example.

Cover 73 is replaced in position.

On depressing lever 4 quadrant 10 rotates pinion 12 through 90°. Consequently spring 18 pulls a tooth 22 of ratchet wheel 21 round and through 90° anti-clockwise regarded from above. Clutch device 25, 26 rotates storage element 60. The bottom articles 64 in the track between the snail-cam 58 and the guide 61 are gradually 45 forced further and further from the vertical through the rectangular orifices 70 as the storage element 60 revolves. In addition the lowest article in each channel 67 is pressed outwardly by the weight of the articles lying above it. Finally when the article comes opposite the stop 80 it falls flat, under pressure of the weight of the articles above since its lower edge is released from guide 61. The article ejected comes to rest horizontally on transverse stop 80, without falling from the machine. In this position the article can easily be withdrawn by the fingers. The article next above it falls vertically and has its lower outer edge caught by stop 80, so that it is held vertically in its channel 67 and 60 on the next downward pressure on lever 4 becomes engaged between cam 58 and guide 61, and so on.

The engagement of spring 55 with a tooth of the ratchet wheel 21 prevents the ratchet wheel 65 21 from rotating clockwise, regarded from above, when the pinion 12 and quadrant return to their original position.

In modified forms of device the arrangement and number of storage channels 67 and corresponding rotating mechanism may be so modified as to deliver at other fractions of a turn, e. g., $\frac{1}{8}$.

What I claim and desire to secure by Letters Patent is:

1. A machine for displaying and dispensing stacked soap tablets or the like articles comprising a base member having a delivery side, a track along which is guided the lowermost article of the stack, said track being formed between a snail cam and a guide secured to the top of said base member, a discharge aperture to said track, a storage element, for the stacked articles rotatably secured above said snail cam, and with its axis of rotation perpendicular to the plane of said snail cam, means for rotating said storage element, a discharge orifice to said storage element, a bridge-member crossing the said discharge orifice, the arrangement being such that when the rotating mechanism is operated, the guiding face of the snail cam displaces the centre of gravity of the lowermost stacked tablet, the cam moving the bottom of the tablet outwards whilst the bridge member retains the top of the tablet in its original position thereby displacing the centre of gravity of the tablet, so that the weight of the tablet tends to pull the tablet automatically down into a discharge position, the tablet being retained on the slant by the internal face of the guide, until the tablet is rotated in line with the delivery aperture, then the resistance of the outside guide is removed, and the weight of the tablet automatically pulls the tablet down into the delivery position.

2. A machine according to claim 1, a stop being provided on the base, the discharge outlet being provided between the extreme end of the guide and said stop whereby the article is permitted to come to rest horizontally partly in the column and partly outside it to facilitate manual withdrawal, the stop acting as a lock when in engagement with the article to prevent the column being rotated in the delivery direction, whilst the article is in the delivery direction. 10

3. In the means for rotating the storage element of a machine according to claim 1, a rotatable spindle supporting said storage element, a ratchet wheel in driving connection with said spindle, and a spring pawl engaging said ratchet wheel, said pawl being operated by a lever arrangement normally manually accessible for rotating the storage element. 15

4. In the means for rotating the storage element of a machine according to claim 1, a rotatable spindle supporting said storage element, a ratchet wheel in driving connection with said spindle and a spring pawl engaging said ratchet wheel to lock the wheel against rotation in a direction opposite to the delivery direction. 20 25

BENJAMIN CRAMP.
